UNITED STATES PATENT OFFICE.

FREDERICK KOCH, OF NEWARK, NEW JERSEY, ASSIGNOR TO POWERS ACCOUNTING MACHINE COMPANY, OF NEW YORK, N. Y., A CORPORATION OF DELAWARE.

PIN-BOX FOR SORTING-MACHINES.

1,234,348.

Specification of Letters Patent. Patented July 24, 1917.

Application filed November 1, 1916. Serial No. 128,887.

To all whom it may concern:

Be it known that I, FREDERICK KOCH, a citizen of the United States, residing in Newark, in the county of Essex and State of New Jersey, have invented certain new and useful Improvements in Pin-Boxes for Sorting-Machines, of which the following is a specification.

This invention relates in general to machines for sorting perforated record cards, and more particularly to record card sorting machines of the pin box type in which a single row of pins may coöperate with one of a plurality of rows of data on a record card, the pins also being shiftable to register with any of the rows of data on the record card.

One of the main objects of the present invention is to provide an improved means for locking any of the pins out of operative position.

Still another object of the invention is to provide an improved pin carriage which can, with facility, be shifted from one position to another and yet be securely anchored against displacement when disposed in any one position; and in which the mounting of the pins will be particularly durable without in any way impairing the working efficiency of the pins.

These and other features, capabilities, and advantages of the invention will appear from the subjoined detail description of one specific embodiment thereof, illustrated in the accompanying drawings in which—

Figure 1 is a plan view illustrating the pin carriage in operative position.

Fig. 2 is a fragmental side elevation of the parts illustrated in Fig. 1.

Fig. 3 is a transverse section on the line 3—3 of Fig. 1.

Fig. 4 is a fragmental section on the line 4—4 of Fig. 3.

Fig. 5 is a fragmental section on the line 5—5 of Fig. 3.

Fig. 6 is a detached view of the pin anchoring plate.

Fig. 7 is a fragmental section illustrating certain of the pins anchored in raised position.

In the embodiment illustrated there is shown a sorting machine of the type having a guide plate 11 and a die plate 12, each having a plurality of rows of perforations 13 registering with one another. Below the corresponding perforations of each row there

extends a common deflecting bar 14. Each of the deflecting bars 14 is connected to a deflector (not shown) controlling the entrance to a sorting compartment (not shown), the arrangement being such that when a card is sorted a bar 14, corresponding to the perforation in the card of the row being sorted, will be deflected. Thereupon the card thus analyzed will be fed forward into contact with the deflector (not shown) and be directed into a corresponding compartment (not shown). By this arrangement the cards may be grouped in the compartments according to their perforations.

The plates 11 and 12 are stationary relative to the bars 14. At the ends of the guide plate 11 are disposed the card controlling rollers 15 and 16. Along the longitudinal sides of the guide plate 11 are disposed the guide rails 17 and 18 for the pin carriage hereinafter to be described.

Mounted to reciprocate vertically relative to the die plate 11, there is provided the frame F having the end pieces 19 and 20 and the side pieces 21 and 22 properly secured to one another. The end pieces have vertical extensions 23 and 24 which are provided with cam rollers 25 and 26 respectively for engagement with cams (not shown), whereby the frame F is vertically reciprocated.

On the side pieces 21 and 22 of the frame F is slidably mounted the pin carriage C, which comprises the upper plate 27, the ends of which extend across the top of the side pieces 21 and 22, and the lower plate 28, the ends of which extend across the lower edges of the side pieces 21 and 22. For securing the plates 27 and 28 in alignment with one another, the blocks 29 and 30 are provided which are preferably disposed adjacent to the side pieces 21 and 22, thereby assisting to guide the carriage C in proper alignment relative to the frame F. The plate 27 is provided with a row of openings in alignment with a row of openings in the plate 28 to accommodate the pins 31. The pins 31 are provided with heads 32 disposed between the plates 27 and 28 and springs 33 mounting such pins and strained between the plate 27 and the heads 32, whereby the pins 31 are normally maintained in depressed position with their analyzing ends 34 disposed adjacent to the plate 11, the pins 31 being limited in their downward

movement by the heads 35 disposed above the plate 37 and resting in the seats 36 formed in the upper surface of the plate 27. Above the heads 35, the pins 31 are provided 5 with the heads 37 which are disposed above the non-analyzing locking plates 38 and 39. When the heads 35 are disposed in the seats 36, the upper surface of the heads 35 will be flush with the upper surface of the plate 10 27 so as to permit the locking plate 40 to coöperate with such heads 35 to lock the pins 31 in analyzing position.

In the operation of the device, the carriage C will be movable to register its 15 row of pins 31 with any of the rows of perforations 13 in the plates 11 and 12. For anchoring the carriage C at any of these several positions, there are provided the racks 41 and 42 to the outside of the side 20 pieces 21 and 22, respectively. For coöperating with the racks 41 and 42, the pins 43 and 44 are provided which are disposed in the bores of the finger pieces 45 and 46 respectively, being spring pressed against 25 the teeth of the racks 41 and 42, respectively. The finger pieces 45 and 46 are secured to the ends of the plate 27.

The locking plate 40 is slidably mounted on the plate 27, the ends thereof being reciprocally mounted in the recesses formed in the edge of the plates 47 and 48 secured to the plate 27. The plate 40 is provided with a plurality of recesses 49 which receive the stems of the pins 31 when the plate 40 is 35 actuated to lock the pins 31 in analyzing position, the portions of the plate 40 on the sides of the recesses 49 coöperating with the heads 35 to anchor the pins 31 in analyzing position.

40 For actuating the plate 40, the bell crank 50 is secured to the shaft 51 mounted between the blocks 29 and 30. The upwardly extending arm 52 of the bell crank 50 extends through the opening 53 in the plate 45 40, and its laterally extending arm 54 has a slot 55 through which the pin 56 on the standard 57 passes. The standard 57 passes up through slots formed in the plates 28 and 27 and the elongated slot 58 in the plate 40.

50 The standard 57 is anchored against vertical displacement by the rail 17, there being two studs 59 and 60 extending from said standard 57, the stud 59 above the rail 17 and the stud 60 below the rail 17. Secured 55 to the standard 57 and extending therefrom is the covering member 61, between which the lower ends of the pins 31 are disposed, the covering member 61 extending from the standard 57 over to and beyond the rail 18.

60 For the purpose of maintaining the covering member 61 and carriage C in alinement with one another, the pin 62 secured to the carriage C extends therethrough and between the covering 61.

65 The locking plates 38 and 39 are pivotally

connected to the post 63 which is disposed in the middle of the carriage C. The plates 38 and 39 are each provided with a plurality of concentrically curved slots 64 along one side thereof to receive the pins 31 below the 70 heads 37 when the pins 31 are in analyzing position, and to receive such pins 31 as are to be locked out of analyzing position below the heads 35. The concentric slots vary in length, the shortest being disposed nearest 75 the post 63, while the others vary in length according to the distance they are removed from the post 63. The slots 64 remotest from the post 63 have rearward extensions 64' to receive the pins 65 just below 80 their heads 66. The plates 38 and 39, at the ends of the slots 64', are provided with depressions to coöperate with the heads 66 of the pins 65 to lock the plates 38 and 39 in their set position.

85 The pins 65 extend through the plates 27 and 28 and have heads 67 disposed between the plates 27 and 28 which serve as lower abutments for the springs 68 which are mounted on the pins 65 and are strained 90 between such heads 67 and the plate 27, thereby to normally maintain the pins 65 in descended position.

95 The operation of the elements constituting the present invention is substantially as follows: The carriage C may be shifted along the rails 17 and 18, the spring pressed pins 43 locating and defining the position of such carriage C for registration of its pins 31 with a row of perforations 13. In 100 such position, all of the cards thus passed through the machine that have a perforation corresponding to a perforation in the row of perforations in registration will be actuated, and properly fed into a sorting 105 compartment, while the other cards will all be collected in the rejected compartment.

110 When the card is positioned between the plates 11 and 12, the cam will be so timed to engage the cam rollers 25 and 26 to depress the frame F and thereby bring the lower active ends of the pins 31 into engagement with the card and permit those pins that find perforations to pass therethrough and the others to rest on the card. Simultaneously with this descent of the frame F, the bell crank 50 will be rocked, the standard 57 being fixed relative to the vertical movement of the frame F, and thereby draw the locking plate 40 to bring its recesses 49 into engagement with the pins 31 and over the head 35 of that pin that has found a perforation and passes therethrough, so that the sides of the plate 40 around the recess 49 engaging the particular pin will engage the head 35 of such pin and thereby lock it against upward movement. In the further descent of the frame F that pin 31 that is so locked by the plate 40 will then engage the bar disposed below it and thereby ac- 115 120 125 130

tuate the deflector actuating means to set a deflector (not shown) for receiving the card after it has been discharged from the plates 11 and 12.

5 On the ascent of the frame F the locked pin 31 will, of course, again be released and permitted to rise with the remaining pins 31.

For locking any one of the pins 31 out of analyzing position, the plates 38 and 39 10 have been provided. For this purpose the plate 38 or the plate 39 may be swung around the post 63 by engaging the finger piece 68 or 69 of the plates 38 or 39, respectively, thereupon raising the pin 31 to 15 be locked a sufficient distance so that its head 35 will be disposed above the level of the plates 38 and 39, and thereupon return such plate 38 or 39 so that it will engage the raised pin below its head 35 and the 20 other pins below their heads 37, as formerly. This raised pin 31 will then be locked out of position for engagement with the card passing between the plates 11 and 12.

It is obvious that various changes and 25 modifications may be made to the details of construction without departing from the general spirit of the invention.

I claim:—

1. In a machine for sorting perforated 30 record cards having a plurality of rows of data, the combination with a card support having a plurality of openings corresponding to the rows of data on the card, of a carriage, analyzing pins mounted on said carriage for registering with the openings in 35 said card support, means for depressing said pin carriage thereby to pass the pin finding a perforation in the card being sorted through such perforation, deflector actuating bars disposed below said card support 40 to be actuated by the pin passing through a perforation, heads on said pins, and plates for coöperating with said heads to anchor said pins out of analyzing position.

2. In a machine for sorting perforated 45 record cards having a plurality of rows of data, the combination with a card support having a plurality of openings corresponding to the rows of data on the card, of a carriage, analyzing pins mounted on said carriage for registering with the openings in 50 said card support, means for depressing said pin carriage thereby to pass the pin finding a perforation in the card being sorted through such perforation, deflector actuating bars disposed below said card support 55 to be actuated by the pin passing through a perforation, a frame vertically slidable 60 on which said carriage is mounted, heads removed from the upper ends of said pins, a locking plate for passing over the head of the pin finding a perforation, and means for actuating said plate whenever the frame 65 is reciprocated comprising a bell crank piv-

otally mounted to the frame and a standard fixed against vertical displacement relative to the frame, the bell crank connecting said plate with said standard so that the vertical reciprocation of said frame will actuate 70 said locking plate.

3. In a machine for sorting perforated 75 record cards having a plurality of rows of data, the combination with a card support having a plurality of openings corresponding to the rows of data on the card, of a carriage, analyzing pins mounted on said carriage for registering with the openings in 80 said card support, means for depressing said pin carriage thereby to pass the pin finding a perforation in the card being sorted through such perforation, deflector actuating bars disposed below said card support 85 to be actuated by the pin passing through a perforation, heads on said pins, a frame vertically slidable on which said carriage is mounted, and a plate pivotally connected to said frame and having concentric slots to receive said pins below said heads thereby to lock the pins out of analyzing position.

4. In a machine for sorting perforated 90 record cards having a plurality of rows of data, the combination with a card support having a plurality of openings corresponding to the rows of data on the card, of a carriage, analyzing pins mounted on said carriage for registering with the openings in 95 said card support, means for depressing said pin carriage thereby to pass the pin finding a perforation in the card being sorted through such perforation, deflector actuating bars disposed below said card support 100 to be actuated by the pin passing through a perforation, a frame vertically slidable on which the carriage is mounted, means for resiliently maintaining said pins in depressed position, heads on said pins, and plates pivotally connected to said frame and 105 having concentric slots to receive said pins below said heads thereby to lock the pins out of analyzing position.

5. In a machine for sorting perforated 115 record cards having a plurality of rows of data, the combination with a card support having a plurality of openings corresponding to the rows of data on the card, of a carriage, analyzing pins mounted on said carriage for registering with the openings in 120 said card support, means for depressing said pin carriage thereby to pass the pin finding a perforation in the card being sorted through such perforation, deflector actuating bars disposed below said card support 125 to be actuated by the pin passing through a perforation, a frame vertically slidable on which the carriage is mounted, means for resiliently maintaining said pins in depressed position, heads on said pins, plates pivotally connected to said frame and 130

4
having concentric slots to receive said pins below said heads thereby to lock the pins out of analyzing position, and means for anchoring said pivotal plates in pin locking position.

5. In a machine for sorting perforated record cards having a plurality of rows of data, the combination with a card support having a plurality of openings corresponding 10 to the rows of data on the card, of a carriage, analyzing pins mounted on said carriage for registering with the openings in said card support, means for depressing said pin carriage thereby to pass the pin finding a perforation in the card being sorted through such perforation, deflector actuating bars disposed below said card support to be actuated by the pin passing through a perforation, a frame vertically slidable on which 15 the carriage is mounted, means for resiliently maintaining said pins in depressed position, heads on said pins, plates pivotally connected to said frame and having concentric slots to receive said pins below said heads thereby to lock the pins out of analyzing position, extensions on some of said slots, and locking pins resiliently connected to said frame and coöperating with said extensions to anchor said pivotal plates in pin locking 20 position.

6. In a machine for sorting perforated record cards having a plurality of rows of data, the combination with a card support having a plurality of openings corresponding 25 to the rows of data on the card, of a carriage, analyzing pins mounted on said carriage for registering with the openings in said card support, means for depressing said pin carriage thereby to pass the pin finding a perforation in the card being sorted through such perforation, deflector actuating bars disposed below said card support to be actuated by the pin passing 30 through a perforation, a vertically slidable frame on which said carriage is mounted, means for normally maintaining said pins in depressed position, heads on said pins, a locking plate for passing over the head of the pin finding a perforation, and means for 35 actuating said plate whenever the frame is reciprocated, and a second plate disposed above said first locking plate for locking said pins out of analyzing position, the pins to be locked out of analyzing position being 40 raised so that said heads will be disposed above said second locking plate.

7. In a machine for sorting perforated record cards having a plurality of rows of data, the combination with a card support having a plurality of openings corresponding 45 to the rows of data on the card, of a carriage, analyzing pins mounted on said carriage for registering with the openings in said card support, means for depressing said pin carriage thereby to pass the pin finding a perforation in the card being sorted through such perforation, deflector actuating bars disposed below said card support to be actuated by the pin passing 50 through a perforation, a vertically slidable frame on which said carriage is mounted, means for normally maintaining said pins in depressed position, heads on said pins, a locking plate for passing over the head of the pin finding a perforation, and means for actuating said plate whenever the frame is reciprocated, and a second plate disposed above said first locking plate for locking said pins out of analyzing position, the pins to be locked out of analyzing position being 55 raised so that said heads will be disposed above said second locking plate.

8. In a machine for sorting perforated record cards having a plurality of rows of data, the combination with a card support having a plurality of openings corresponding 60 to the rows of data on the card, of a carriage, analyzing pins mounted on said carriage for registering with the openings in said card support, means for depressing said pin carriage thereby to pass the pin finding a perforation in the card being sorted through such perforation, deflector actuating bars disposed below said card support to be actuated by the pin passing 65 through a perforation, a vertically slidable frame on which said carriage is mounted, means for normally maintaining said pins in depressed position, heads on said pins, a locking plate for passing over the head of the pin finding a perforation, and means for actuating said plate whenever the frame is reciprocated, and a second plate disposed above said first locking plate for locking said pins out of analyzing position, the pins to be locked out of analyzing position being 70 raised so that said heads will be disposed above said second locking plate, and means for locking said second locking plate in anchoring position.

9. In a machine for sorting perforated record cards having a plurality of rows of data, the combination with a card support having a plurality of openings corresponding 75 to the rows of data on the card, of a carriage, analyzing pins mounted on said carriage for registering with the openings in said card support, means for depressing said pin carriage thereby to pass the pin finding a perforation in the card being sorted through such perforation, deflector actuating bars disposed below said card support to be actuated by the pin passing 80 through a perforation, a vertically slidable frame on which said carriage is mounted, means for normally maintaining said pins in depressed position, heads on said pins, a locking plate for passing over the head of the pin finding a perforation, and means for actuating said plate whenever the frame is reciprocated, and a second plate disposed above said first locking plate for locking said pins out of analyzing position, the pins to be locked out of analyzing position being 85 raised so that said heads will be disposed above said second locking plate, and means for locking said second locking plate in anchoring position.

10. In a machine for sorting perforated record cards having a plurality of rows of data, the combination with a card support having a plurality of openings corresponding 90 to the rows of data on the card, of a carriage, analyzing pins mounted on said carriage for registering with the openings in said card support, means for depressing said pin carriage thereby to pass the pin finding a perforation in the card being sorted through such perforation, deflector actuating bars disposed below said card support to be actuated by the pin passing 95 through a perforation, a vertically slidable frame on which said carriage is mounted, means for normally maintaining said pins in depressed position, heads on said pins, a locking plate for passing over the head of the pin finding a perforation, and means for actuating said plate whenever the frame is reciprocated, and a second plate disposed above said first locking plate for locking said pins out of analyzing position, the pins to be locked out of analyzing position being 100 raised so that said heads will be disposed above said second locking plate, and means for locking said second locking plate in anchoring position.
